United States Patent Office

Des. 224,848
Patented Sept. 26, 1972

224,848

CARTRIDGE COMB

Nicholas D. McKay, 5314 Territorial Road,
Grand Blanc, Mich. 48439

Filed June 29, 1970, Ser. No. 23,713

Term of patent 14 years

Int. Cl. D28—03
U.S. Cl. D86—8

FIG. 4

FIG. 2

FIG. 3

FIG. 1

FIG. 1 is a perspective view of a cartridge comb showing my new design, the side opposite being a mirror image thereof.

FIG. 2 is a side elevational view of the cartridge portion thereof; the side opposite being a mirror image thereof.

FIG. 3 is an end elevational view of the cartridge portion, the side opposite being a mirror image thereof; and

FIG. 4 is a side elevational view of the cartridge comb with the cartridge portion removed.

I claim:

The ornamental design for a cartridge comb, as shown and described.
